US00D936710S

(12) **United States Design Patent** (10) **Patent No.:** **US D936,710 S**
(45) **Date of Patent:** **** Nov. 23, 2021**

(54) **LAND CLEARING TOOL INTERFACE**

(71) Applicant: **Fecon, LLC**, Lebanon, OH (US)

(72) Inventors: **Jeffrey Stanley**, Lebanon, OH (US);
Robert Hentz, Hamilton, OH (US)

(73) Assignee: **Fecon, LLC**, Lebanon, OH (US)

(**) Term: **15 Years**

(21) Appl. No.: **29/786,086**

(22) Filed: **May 28, 2021**

Related U.S. Application Data

(60) Continuation of application No. 29/764,864, filed on Jan. 4, 2021, which is a division of application No. 29/650,678, filed on Jun. 8, 2018, now Pat. No. Des. 914,064, which is a division of application No. 29/611,032, filed on Jul. 18, 2017, now Pat. No. Des. 821,455, which is a division of application No. 29/571,065, filed on Jul. 14, 2016, now Pat. No. Des. 795,931, which is a division of application No. 29/560,329, filed on Apr. 5, 2016, now Pat. No. Des. 791,195, which is a division of application No. 29/466,991, filed on Sep. 13, 2013, now Pat. No. Des. 757,124, which is a continuation of application No. 12/918,677, filed as application No. PCT/US2009/034872 on Feb. 23, 2009, now Pat. No. 8,540,033.

(57) **CLAIM**

The ornamental design of a land clearing tool interface, as shown and described.

DESCRIPTION

FIG. 1 is a left perspective view of a land clearing tool interface;

FIG. 2 is a right rear perspective view thereof;

FIG. 3 is a top view thereof;

FIG. 4 is a left side view thereof;

FIG. 5 is a front view thereof;

FIG. 6 is a right side view thereof;

FIG. 7 is a back view thereof; and,

FIG. 8 is a bottom view thereof.

The broken line showing in the drawings is included for the purpose of illustrating portions of the land clearing tool interface and forms no part of the claimed design. The dot-dash broken lines represent the bounds of the claimed design.

1 Claim, 3 Drawing Sheets
